UNITED STATES PATENT OFFICE.

ADOLPH SCHERTZ, OF YOUNGSTOWN, OHIO.

PROPELLER.

Application filed January 4, 1929. Serial No. 330,308.

The present invention relates to propellers of a type adapted particularly for use upon aeroplanes, but which also embodies features which permits of the propeller in driving ships and for other purposes where propellers of this character are employed.

One of the important objects of the invention is to provide a propeller embodying a plurality of blades having the leading 10 or forward edge thereof rolled in a manner whereby to create a vacuum upon the forward surface of the blade to counteract any pressure encountered during the forward movement of the propeller through the air 15 or water.

A further object of the invention is to provide reinforcing ribs for each of the propeller blades arranged in a manner to strengthen the blades and at the same time 20 to offer no added resistance during the operation of the propeller.

A still further object of the invention is to provide a propeller by means of which the air or water through which the same 25 is travelling will be discharged in a direction substantially axially with respect thereto and equally distributed against the aeroplane or other object upon which the propeller is mounted, whereby to assist in the 30 stabilization thereof.

Other objects and advantages reside in the special construction, combination and arrangement of the various elements forming the invention as more fully hereinafter described and claimed, reference being had to the accompanying drawings forming part hereof wherein like numerals refer to like parts throughout, and in which:

Figure 1 is a front elevational view;

40 Figure 2 is a rear elevational view;

Figure 3 is an elevational view looking toward the leading or forward edge of one of the blades,

45 Figures 4 and 5 are transverse sectional views through one of the blades, taken respectively along the lines 4-4 and 5-5 of Figure 1,

Figures 6 is a transverse sectional view through the center of the propeller, and

50 Figure 7 is a fragmentary perspective view of the end of one of the blades illustrating the pocket formed on the forward face of the blade by the rolled leading edge thereof.

55 Referring to the drawings in detail for

the purpose of illustration, I have illustrated a practical form of the invention which embodies a hub 5 having a bore 6 extending therethrough adapted for receiving the end of a propeller shaft for driving 60 the propeller in the usual manner well known in the art.

A plurality of propeller blades 7 extend tangentially with respect to the hub, the present embodiment of the invention illustrating the propeller equipped with four of such blades, it being understood however that the propeller may embody any desired number of blades to produce more efficient results under certain conditions.

70 The trailing edge of each blade, indicated at 8 extends radially from the axis of the hub and are arranged so that the trailing edge of the blades at the opposite side of the propeller are disposed in alinement at 75 diametrically opposite sides of the hub.

The leading or forward edge of each of the blades indicated at 9 is of an arcuate formation as clearly illustrated in Figures 80 1 and 2 of the drawings and are formed with a rolled edge 10 extending forwardly of the front surface of the blade and likewise formed in an arc eccentric to the arc of the leading edge of the blade.

85 The inner end of the arc formed by the rolled edge 10 passes through the axis of the hub 5, as more clearly shown in Figure 1 of the drawing whereas the outer end of said arc merges with the arc formed by the leading edge 9 inwardly of the extreme 90 outer end of the blade.

A rib 11 extends longitudinally of each of the blades and is disposed upon the forward surface thereof whereby to form a 95 longitudinally extending trough 12 in the rear surface of the blade. The rib 11 is likewise of an arcuate formation with its inner end passing through the axis of the hub and its outer end merging with the outer end of the rolled edge 10.

100 The area of the front surface of each of the blades, between the leading edge 9 and the rib 11 is thus formed into a pocket 13. As more clearly illustrated in Figures 4 and 5 of the drawings, the forward face of the blade within which the pocket is formed, is concaved as shown at 14, the rear surface of this portion of the blade being likewise convexed.

110 The area of the blade between the rib 11

and the trailing edge 8 is formed with a substantially plane surface, both at the forward and rear sides of the blade and, as more clearly illustrated in Figure 3 of the drawings, the trailing edge 8 of each of the blades inclined rearwardly toward the outer end thereof.

Also by reason of the arcuate formation of the rib 11 the plane surface of each of the blades increases in width toward the outer end thereof. Both the forward and rear surfaces of the blades are provided with transversely extending ribs 15 extending toward each edge of the blades from the ribs 11, the ribs 15 being likewise of a slightly arcuate formation eccentric with respect to the hub. The hub at the forward side of the propeller is externally threaded for receiving a cap 16 secured in position upon the hub 20 against accidental displacement by the set screws 17.

By reason of the pocket 13 formed in the forward surface of each of the blades an air pocket will be created tending to counteract pressure against the forward side of the blade exerted against the propeller as the same moves forwardly.

Also by reason of the arcuate formation of the leading or forward edges of the blade 30 less resistance will be offered thereto as the propeller is rotated.

It will further be apparent that the ribs 15 materially strengthen the blade and maintain the respective plane and concaved surfaces thereof against distortion during the rapid rotation of the propeller, thus by reason of the arcuate formation of these ribs it will be apparent that the same offer no added resistance to the air or water through 40 which the blades are passing.

It is obvious that my invention is susceptible to various changes and modifications in construction without departing from the spirit of the invention or the scope of the 45 appended claims, and I accordingly claim all such forms of the device to which I am entitled.

Having thus described my invention, what I claim as new is:

50 1. A propeller comprising a hub and a plurality of blades extending outwardly therefrom with the trailing edges of the oppositely disposed blades arranged in alinement and with a lip formed at the leading edge of the blade and extending forwardly over the front surface of the blade.

55 2. A propeller comprising a hub and a plurality of blades extending outwardly therefrom with the trailing edges of the oppositely disposed blades arranged in alinement and with a lip formed at the leading edge of the blade and extending forwardly over the front surface of the blade, said lip of each of the blades likewise being arcu- 60 ately formed and disposed eccentrically with

respect to the arc of the respective leading edges and merging with the leading edges inwardly of the outer ends of the blades.

3. A propeller comprising a hub, a plurality of blades extending outwardly therefrom with the trailing edges of the oppositely disposed blades arranged in alinement and with a lip formed at the leading edge of the blades and extending forwardly over the front surface of the blades, said lip of each of the blades likewise being arcuately formed and disposed eccentrically with respect to the arc of the respective leading edges and merging with the leading edges inwardly of the outer ends of the blades and a rib extending longitudinally of each of the blades with the area of the blade rearwardly of said ribs having a plane surface and the area of the front surface of the blade forwardly of the rib concaved whereby to form a pocket between the lip of the blade and the rib.

4. A propeller comprising a hub, a plurality of blades extending outwardly therefrom with the trailing edges of the oppositely disposed blades arranged in alinement and with a lip formed at the leading edge of the blades and extending forwardly over the front surface of the blades, said lip of each of the blades likewise being arcuately formed and disposed eccentrically with respect to the arc of the respective leading edges and merging with the leading edges inwardly of the outer ends of the blades and a rib extending longitudinally of each of the blades with the area of the blade rearwardly of said ribs having a plane surface and the area of the front surface of the blade forwardly of the rib concaved whereby to form a pocket between the lip of the blade and the rib, said rib also being arcuately shaped and disposed eccentrically with respect to the lip and leading edge and merging at its outer end with the outer end of said lip.

5. A propeller comprising a hub, a plurality of blades extending outwardly therefrom with the trailing edges of the oppositely disposed blades arranged in alinement and with a lip formed at the leading edge of the blades and extending forwardly over the front surface of the blades, said lip of each of the blades likewise being arcuately formed and disposed eccentrically with respect to the arc of the respective leading edges and merging with the leading edges inwardly of the outer ends of the blades and a rib extending longitudinally of each of the blades with the area of the blade rearwardly of said ribs having a plane surface and the area of the front surface of the blade forwardly of the rib concaved whereby to form a pocket between the lip of the blade and the rib, said rib also being arcuately shaped and disposed eccentrically

- with respect to the lip and leading edge and merging at its outer end with the outer end of said rolled edge, and said rib and said lip having their inner ends terminating at 5 the axis of the hub.
6. A propeller comprising a hub, a plurality of blades extending outwardly therefrom with the trailing edges of the oppositely disposed blades arranged in alinement and with 10 a lip formed at the leading edge of the blades and extending forwardly over the front surface of the blades, said lip of each of the blades likewise being arcuately formed and disposed eccentrically with respect to 15 the arc of the respective leading edges and merging with the leading edges inwardly of the outer ends of the blades and a rib extending longitudinally of each of the blades with the area of the blade rearwardly of said 20 ribs having a plane surface and the area of the front surface of the blade forwardly of the rib concaved whereby to form a pocket between the lip of the blade and the rib, said rib also being arcuately shaped and disposed eccentrically with respect to the lip and 25 leading edge and merging at its outer end with the outer end of said lip, and said rib and said lip having their inner ends terminating at the axis of the hub, said plane surface of the blade being of an increased width toward the outer end of the blade and arranged with the trailing edge thereof inclined rearwardly and outwardly, and a plurality of arcuately shaped reinforcing ribs formed on each surface of the blade and disposed eccentrically with respect to the 30 hub. 50
7. A propeller comprising a hub, a plural- 55

60 In testimony whereof I affix my signature.

ADOLPH SCHERTZ.
